ABSTRACT OF THE DISCLOSURE

A ventilation assembly including vapor conveying passage means communicating the interior of the intake manifold of an associated internal combustion engine with a source of crankcase and piston "blow-by" vapors produced by the internal combustion engine and with vacuum actuatable valve means interposed in the vapor conveying passage means and actuatable by engine vacuum to allow free flow of vapors through the passage means in response to an increase in manifold vacuum and to terminate the free flow of vapors through the passage means in response to a low vacuum condition being present in the intake manifold of the associated engine.

The ventilation assembly of the instant invention has been specifically designed for ready mounting on substantially all types of motor vehicle combustion engines presently in use and to perform in such a manner that the crankcase vapor emission and exhaust emission of smog supporting impurities from an associated engine will be greatly controlled.

Further, the ventilation assembly has also been designed to function as a fuel economizer by routing at least some of the combustible crankcase vapors into the intake passages of an associated engine.

The ventilation assembly is constructed in a manner whereby it may be readily operatively associated with substantially all types of conventional internal combustion engines and its operation requiring frequency maintenance or replacement intervals.

The main object of this invention is to provide a ventilation assembly for the crankcase of an internal combustion engine and which will provide desired ventilation as well as route the ventilated crankcase vapors into the intake passages of the associated engine.

Another object of this invention is to provide a ventilation assembly which includes structural features thereof adapting it for use with various types of conventional internal combustion engines.

A still further object of this invention is to provide a crankcase ventilation assembly including structural features thereof which may be adjusted and utilized to slightly modify the crankcase ventilation valve so as to be specifically adapted for use with various types of internal combustion engines.

Another object of this invention is to provide a ventilation valve assembly constructed in a manner such that it may be operatively communicated with a source of crankcase and piston "blow-by" vapors at several locations on an associated internal combustion engine such as the draft tube, rocker arm covers or any fitting specifically provided for establishing communication with the interior of the crankcase.

A final object of this invention to be specifically enumerated herein is to provide a ventilation assembly in accordance with the preceding objects which will conform to conventional forms of manufacture, be of simple construction and automatic in operation so as to provide a

2

device that will be economically feasible, long lasting and relatively trouble-free in operation.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a schematic top plan view of a conventional form of internal combustion engine with which the ventilation valve assembly of the instant invention is operatively associated;

FIGURE 2 is an enlarged fragmentary vertical sectional view taken substantially upon the plane indicated by section line 2—2 of FIGURE 1;

FIGURE 3 is a fragmentary vertical sectional view similar to FIGURE 2 but illustrating a modified form of ventilation valve assembly; and

FIGURE 4 is a fragmentary perspective view of a portion of the valve member utilized in the valve assembly of FIGURE 3.

Referring now more specifically to the drawings the numeral 10 generally designates a conventional form of V-8 internal combustion engine including an intake manifold 12, a pair of rocker arm covers 14 and a distributor assembly generally referred to by the reference numeral 16 including a vacuum advance assembly 18 actuated by a vacuum line 20 communicating the vacuum advance assembly with the interior of the intake manifold 12.

The ventilation valve assembly is referred to in general by the reference numeral 22 and includes a housing assembly referred to in general by the reference numeral 24 including first and second sections 28 and 30 removably secured together by means of suitable fasteners 32.

The first section 28 of the housing section 24 has a flexible diaphragm 34 disposed therein including a central movable portion 36 to which one end of a valve actuator rod 38 is secured in any convenient manner. The diaphragm 34 divides the interior of the housing assembly 24 into first and second compartments 39 and 40 and the housing assembly 24 includes an internally threaded inlet 42 opening into the first compartment 39 and an outlet neck portion 44 opening outwardly of the first compartment 39. Further, the second section 30 defines a conical valve seat 46 at the inner end of the threaded inlet 42 with which a disk-shaped valve head 48 carried by the end of the valve actuating rod 38 remote from the diaphragm 34 is operatively associated. The valve head 48 includes a pair of small bleed passages or bores 50 formed therethrough and a baffle plate 52 is carried by the valve actuating rod 38 intermediate the valve head 48 and the diaphragm 34.

The housing assembly 24 defines a small diameter outwardly projecting neck portion 54 which opens into the second compartment 40 and has one end of a vacuum line 56 secured to its outer end, the other end of the vacuum line 56 being operatively communicated with the vacuum line 20 as at 58.

The first section 28 of the housing assembly 24 also defines a neck portion 60 in whose outer end an abutment sleeve 62 is threadedly engaged, the abutment sleeve 62 having an abutment screw 64 threaded therethrough. The sleeve 62 is threadedly engaged in the outer end of the neck portion 60 and the abutment screw 64 includes a diametrically reduced inner end portion 66 which is received through an abutment washer 68 disposed within the neck portion 60. A compression spring 70 is disposed between the washer 68 and the movable portion 36 of the diaphragm 34 and thereby yieldingly urges the movable portion 36 downwardly as viewed in FIGURE 2 of the drawings. Thus, the spring 70 yieldingly urges the

valve head 48 toward seated engagement with the valve seat 46 at the inner end of the inlet 42.

The threaded inlet 42 has one end of a threaded nipple 72 secured therein and the other end of the nipple 72 is threaded in a fitting 74 carried by and opening into the top of one of the valve or rocker arm covers 14 thus communicating the nipple 72 with the interior of the crankcase (not shown) of the internal combustion engine 10 through the rocker arm cover 14 from which the nipple 72 is supported.

The rocker arm cover 14 on the side of the engine 10 remote from the housing assembly 24 is provided with a conventional oil filler opening or neck (not shown) with which a combined breather cap and closure 78 is removably secured. The nipple 72 includes a laterally directed neck 80 intermediate its opposite ends provided with a manual valve 82 and a small flexible conduit 84 communicates the neck 80 with the interior of the breather cap 78 and therefore also with the interior of the rocker arm 14 from which the breather cap 78 is supported. Finally, a conduit member 86 of larger diameter than the vacuum line 56 has one end thereof secured to the outlet neck portion 44 and the other end thereof secured to a nipple 88 opening into the interior of the intake manifold just under the throttle valves of the carburetor 90 secured on the manifold 12. The fitting 88 may of course open either directly into the intake manifold 12 or through a suitable plate provided for the purpose interposed between the base of the carburetor 90 and the mounting flange of the manifold 12 upon which the carburetor 90 is mounted.

In operation, upon a decrease in manifold vacuum the spring 70 will urge the movable portion 36 downwardly and thus close the valve defined by the valve head 48 allowing only slight communication between the nipple 72 and the conduit or pipe 86 through the bores 50. However, upon an increase of manifold vacuum, the reduced pressure above the movable portion 36 will cause the latter to move upwardly against the biasing force of the spring 70 and thus the valve head 48 to also be lifted toward the full open position. Of course, this will result in free communication of the interior of the nipple 72 with the interior of the conduit 86 and therefore crankcase vapors from the crankcase of the internal combustion engine 10 may flow freely into the intake manifold 12.

As different internal combustion engines have different operating characteristics, the abutment or adjusting screw 64 is provided and may be adjusted as desired to provide the desired biasing action on the movable portion 36 of the diaphragm 34.

With reference now more specifically to FIGURES 3 and 4 of the drawings there may be seen a modified form of ventilation valve assembly generally referred to by the reference numeral 22' and which includes certain components thereof similar to components of the valve assembly 22 and therefore provided with corresponding prime numerals.

Instead of being provided with an outlet neck portion such as neck portion 44 and a neck portion such as neck portion 80, the second section 30' of the valve assembly 22' includes a pair of conduit inlet end portions 86' which open into diametrically opposite portions of the second section 30' and whose inlet terminal ends are beveled as at 87. The valve actuator rod 38', in addition to having the valve head 48' thereon for closing the outlet end of the nipple 72', is provided with a pair of angulated plates 89 apertured as at 91 for engagement with the beveled terminal ends 87. When engaged with and seated against the beveled terminal ends 87, the plates 98 close the inlet end portions 86'. Of course, the inlet end portions 86' comprise end portions of conduits which are adapted to open into the intake manifold 12 beneath the throttle valve of the carburetor 90.

The operation of the ventilation valve assembly 22' is substantially identical to the operation of the valve 75

assembly 22 and the nipple 72' may of course also be provided with a neck portion such as neck portion 80.

What is claimed as new is as follows:

1. In combination with an internal combustion engine of the type including an intake manifold portion under manifold vacuum and disposed downstream from an associated throttle valve, a source of crankcase and piston blow-by vapors, a ventilation assembly comprising housing means defining a vacuum chamber, a diaphragm in said chamber dividing the latter into first and second separate closed compartments, said housing including an inlet opening into said first compartment, first large vapor conveying passage means communicating said inlet with said source, second large vapor conveying passage means communicating the interior of said first compartment with the interior of said manifold for free unrestricted flow of vapors from said chamber into said manifold in response to lower vapor pressure in said manifold, said housing including a valve member movable between first open and second closed positions controlling the free flow of vapor from said first vapor conveying passage means into said first compartment, said diaphragm including a portion movable between first and second positions in response to greater and lesser pressure in said first compartment relative to the pressure in said second compartment and means connecting said movable portion to said valve member for movement of the latter between said first and second positions thereof in response to movement of said movable portion to its first and second positions, means biasing said movable portion toward said second position thereof, and means constantly communicating the interior of said second compartment with the interior of said manifold, said assembly including means defining restricted vapor flow passage means past said valve member communicating said first and second vapor conveying passage means for restricted vapor flow therebetween when said valve member is in said second position.
2. The combination of claim 1 wherein said means biasing said movable portion toward said second position thereof includes means for adjusting the biasing force effected thereby from the exterior of said housing.
3. The combination of claim 1 wherein said restricted vapor flow passage means past said valve member are defined entirely by passage means extending through said valve member.
4. The combination of claim 1 wherein said valve member is operable to open and close said inlet when in said first and second positions thereof.
5. The combination of claim 1 wherein said valve member is operable to control the flow of vapors from said first compartment into said second vapor conveying passage means.
6. The combination of claim 1 wherein said valve member is operable to control the flow of vapors into said first compartment from said first vapor conveying means.
7. The combination of claim 1 wherein said valve member is operable to control the flow of vapors from said first compartment into said second vapor conveying passage means, said second vapor conveying means including a pair of conduit end portions opening into said first compartment, said valve member including portions operable to close said conduit end portions when said valve member is in said second position.
8. The combination of claim 1 including baffle means in said first compartment operable to block the free flow of liquids through said first compartment and into said second vapor conveying passage means.
